(57) CLAIM

What is claimed is the ornamental design for a basketball-shaped die agitator containing a die, as shown and described.

DESCRIPTION

FIG. 1 is a front right perspective view of a basketball-shaped die agitator containing a die;

FIG. 2 is a rear view thereof;

FIG. 3 is a front view thereof;

FIG. 4 is a right view thereof;

FIG. 5 is a left view thereof;

FIG. 6 is a top view thereof; and,

FIG. 7 is a bottom view thereof.

In the drawings, broken lines form no part of the claimed design.
